UNITED STATES PATENT OFFICE.

PHILO M. GELATT, OF LA CROSSE, WISCONSIN

BULB FOR TEMPERATURE-INDICATING INSTRUMENTS.

1,266,580.

Specification of Letters Patent.

Patented May 21, 1918.

Application filed October 1, 1917. Serial No. 194,151.

To all whom it may concern:
Be it known that I, PHILO M. GELATT, a citizen of the United States of America, residing at La Crosse in the county of La 5 Crosse and State of Wisconsin, have invented certain new and useful Improvements in Bulbs for Temperature-Indicating Instruments, of which the following is a specification, reference being had therein 10 to the accompanying drawings.

In the use of temperature indicators, especially for high speed motors, wherein a bulb which is connected to the indicating mechanism by a slender conduit is inserted 15 through the wall of the motor into the lubricant or cooling liquid thereof, the vibrations of the motor frequently cause the connection between the bulb and the conduit to crystallize and snap off or leak.

20 This invention relates to a bulb for instruments of the character noted together with means for connecting and supporting the same in operative position, arranged and fitted to prevent vibration and avoid 25 subsequent deterioration of the connection.

The invention consists in the matters hereinafter set forth and more particularly pointed out in the appended claims.

30 In the drawings,
Figure 1 is a view partially in elevation and partially in section, of a device embodying features of the invention;

Fig. 2 is a view in end elevation thereof;

Fig. 3 is a view, partially in side elevation and partially in section, of a modification of the device, and

Fig. 4 is a view in end elevation of the modification.

As herein shown in preferred form, a 40 tubular bulb 1 of suitable material with a flange 2 at one end thereof has an enlarged spindle 3 extending therefrom to the end of which a slight conduit tube 4 is secured.

An exteriorly screwthreaded bushing 5 45 has an inner flange 6 against which the flange of the bulb is secured by a jam nut 7 which encircles and steadies the nipple 3, the bushing itself being properly secured in the wall 8 through which the bulb is to be 50 inserted, there being an outer flange 9 for seating the bushing when screwed home.

The nipple 3 is of sufficient length to protrude slightly beyond the nut 7 and thereby prevent any sidewise pressure of any sort being exerted upon the tube 4.

Or if preferred, as shown in the modification Figs. 3 and 4, a bulb 10 with a flange 11 and screwthreaded nipple or enlarged stem 12 is inserted through an exteriorly screwthreaded bushing 13, the flange 11 being brought against the shoulder formed by the inner face thereof by a jam nut 14 engaging the screwthreads of the nipple 12. The usual conduit or pipe 15 extends from the nipple.

As a result of this construction the bulb is bodily inserted through the wall of the motor or receptacle in which it is to be secured, and is firmly held by the bushing and jam nut and flange of the bulb in such a 70 way that any vibration is minimized and its effect on the protruding cylinder conduit is rendered practically *nil*. The result is of course obtained by the broad lateral bearing afforded by the flange of the bulb, contacting as it does with the annular shoulder on the inner end portion of the bushing, against which it is firmly held by the action of the jam nut. The device is readily removed for inspection and is found to be 80 durable.

Obviously, changes in the details of construction may be made without departing from the spirit of my invention and I do not care to limit myself to any particular 85 form or arrangement of parts.

What I claim is:

1. A bulb fitting for temperature and pressure indicating instruments comprising a bulb, a nipple extending from the unsealed end thereof, a bearing flange on the latter end, a supporting bushing through which the nipple extends and against an end face of which the bearing flange contacts, and a jam nut in screwthreaded engagement 90 with the bushing adapted to force the flange to seat, the nipple protruding beyond the jam nut.

2. A bulb fitting for temperature and pressure indicating instruments comprising a bulb, having an annular flange at the unsealed end thereof, a nipple extending from

the unsealed end thereof, a bushing adapted to be inserted in an opening of a supporting wall and provided near one end with a bearing face for receiving the nipple flange, 5 a slender tube extending from the nipple and a jam nut through which the nipple protrudes adapted to force the flange of the

bulb against the bearing face of the bushing. In testimony whereof I affix my signature in the presence of two witnesses.

PHILO M. GELATT.
